(57) CLAIM

The ornamental design for a glove, as shown and described.

DESCRIPTION

FIG. 1 is a plan view of the back of a glove according to this invention;

FIG. 2 is a plan view of the front of a glove according to this invention; and,

FIG. 3 is a side view of the left side of a glove according to this invention.

The portions of the drawing that are shown in dashed lines are not considered to be part of, or a limitation on the instant claimed design.

The broken line showing of portions of the glove is for illustrative purposes only and forms no part of the claimed design as well as the broken line(s) which define the bounds of the claimed design form no part thereof.
